CLAIM

The ornamental design for a hot air styling brush, as shown and described.

DESCRIPTION

FIG. 1 is a perspective view of a hot air styling brush, showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines shown in the drawings illustrate features of the article that form no part of the claimed design.

1 Claim, 6 Drawing Sheets(56)
